A. D. Hoffman

UNITED STATES PATENT OFFICE.

A. D. HOFFMAN, OF BELLEVILLE, MICHIGAN.

CIDER-MILL.

Specification of Letters Patent No. 26,037, dated November 8, 1859.

To all whom it may concern:

Be it known that I, A. D. HOFFMAN, of Belleville, in the county of Wayne and State of Michigan, have invented a new and Improved Cider Mill and Press; and I do hereby declare that the following is a full, clear, and exact description of the same, reference being had to the annexed drawings, making a part of this specification, in which—

10 Figure 1, is a side sectional view of my invention taken in the line x, x , Fig. 2. Fig. 2, is a plan or top view of ditto.

Similar letters of reference indicate corresponding parts in the two figures.

15 The object of this invention is to obtain within limited dimensions a machine that will crush apples and express the juice therefrom with but a small expenditure of power, the crushing and expressing operation being performed simultaneously and the juice separated from the pomace.

The invention consists in the employment or use of two crushing rollers one being toothed and the other correspondingly re-
25 cessed to receive the teeth of the former one, and using, in connection with the crushing rollers, two pressure rollers and an endless apron, one pressure roller being provided with yielding longitudinal bars and the
30 whole arranged and combined to operate in such a manner as to effect the desired result.

To enable those skilled in the art to fully understand and construct my invention I
35 will proceed to describe it.

A, represents a rectangular frame which may be constructed in any proper way to support the working parts. On the upper part of this frame the rollers B, B', are placed transversely and side by side. The roller B, is provided with teeth a , which are placed on the roller in spiral rows, as shown plainly in Fig. 2. The roller B', has recesses b , made in its periphery the re-
40 cesses being also formed in spiral rows corresponding inversely with the position of the teeth a , and of such dimension as to receive the same as the rollers rotate. A hopper C, is placed on the frame A, directly
45 over the rollers B, B'.

On the shaft of the roller B, at the outer side of the frame A, there is a toothed wheel D, into which a pinion b' , gears. This pinion b' , gears into a wheel c , which is on

the shaft of a roller E, placed transversely in the frame A, and parallel with the roller B.

The roller E, has a series of longitudinal and radial grooves d , made in it and in each groove, a bar e , is placed, said bars having springs f , bearing against their inner sides and having a tendency to keep the bars thrust outward from the periphery of the roller. The roller E, is covered by a piece of cloth or canvas g , which is allowed to fit loosely on the roller E.

Directly below the roller E, and in the same plane there is a roller F. The two rollers E, F, are about equal in diameter and they are made to rotate simultaneously in consequence of a wheel h , gearing into the wheel c . The roller F, has a smooth periphery.

G, is an endless apron which passes between the rollers E, F, and around rollers i, i , in the frame A, said apron also passing underneath a trough H, in the lower part of the frame.

The pinion b' , is placed on one end of a shaft I, the opposite end having a toothed wheel J, on it, which gears into a pinion j , on the driving shaft K.

The operation of the machine is as follows: The apples are placed in the hopper C, and the shaft K, rotated by hand or any convenient power. The apples are crushed in passing between the rollers B, B, the teeth a , and recesses b , facilitating the crushing operation by insuring a uniformity of action in consequence of their spiral position, and preventing all clogging of the apples in the hopper as the teeth serve as agitators. The crushed apples fall on the apron G, which conveys them between the rollers E, F, the latter expressing the juice from them which falls into the trough H. The expressing of the juice from the crushed apples is greatly facilitated by the spring or elastic bars e , and cloth or canvas g , which give an intermittent pinching or pressing action, which adds to the efficiency of the rollers. The juice falls at the inner sides of the rollers, the pomace only passing between them, the pomace being discharged at the depressed or lowest part of the belt.

I am aware that crushing and pressure rollers and also endless aprons have been used for crushing apples, and expressing the

juice therefrom, and I do not claim such device irrespective of the peculiarities connected with the rollers as herein described.

I claim therefore as new and desire to secure by Letters Patent,

The combination of the crushing rollers B, B', pressure rollers E, F, and endless aprons G, when the crushing rollers B, B', are provided respectively with teeth *a*, and

recesses *b*, and the pressure roller E, provided with the yielding bars *e*, and canvas covering *g*, substantially as and for the purpose set forth.

A. D. HOFFMAN.
